UNITED STATES PATENT OFFICE

165,730

STROLLER

John Abahazi, Jr., Lorain, Ohio

Application August 8, 1951, Serial No. 16,209

Term of patent 7 years

(Cl. D14—14)

To all whom it may concern:

Be it known that I, John Abahazi, Jr., a citizen of the United States, residing at Lorain, in the county of Lorain, and State of Ohio, have invented a new, original, and ornamental Design for a Stroller, of which the following is a specification, reference being had to the accompanying drawings, forming part thereof.

The appearance of the opposite side of Figure 1 is substantially the same as the side shown.

I claim:

The ornamental design for a stroller, as shown and described.

JOHN ABAHAZI, JR.
